UNITED STATES PATENT OFFICE.

ALFRED L. EUSTICE, OF CHICAGO, ILLINOIS.

FUSE.

1,330,066.

Specification of Letters Patent. Patented Feb. 10, 1920.

Application filed March 7, 1918. Serial No. 220,963.

To all whom it may concern:

Be it known that I, ALFRED L. EUSTICE, a citizen of the United States, and resident of Chicago, in the county of Cook and State 5 of Illinois, have invented certain new and useful Improvements in Fuses, of which the following is a specification.

This invention relates to fuses.

One of the objects of the invention is to 10 increase the sensitiveness of fusible elements whereby definite results may be had.

Another object is to form a fuse air chamber in a novel manner to meet the various requirements for successful commercial 15 operation.

These and other objects are accomplished by providing in combination, a fusible member having a portion thereof cupped for providing air space within the member, and 20 means for inclosing the air space for confining generated heat.

The invention is illustrated on the accompanying sheet of drawings in which,

Figure 1 is a longitudinal sectional view 25 of a fuse embodying my invention.

Fig. 2 is a transverse sectional view, taken on the plane of line 2—2 of Fig. 1.

Fig. 3 is a longitudinal sectional view, taken at a different angle from that shown 30 in Fig. 1.

Fig. 4 is a fragmentary sectional view, taken on the plane 4—4 of Fig. 1, and

Fig. 5 is a fragmentary plan view of a 35 fusible member cupped to form an air space.

The various novel features of my invention will be apparent from the following description and drawings and will be particularly pointed out in the appended claims.

Referring to the figures of the drawings, 40 it will be noted that I have shown a fuse including a cylindrical casing 10, preferably of insulating material, the ends of which casing are closed by metallic caps 11. Extending diametrically through the casing 45 and electrically connected to the caps are terminal straps 12, to which are connected the ends of a fusible element or link 13. The casing contains any suitable insulating material 14, such as asbestos, or the like, for dissipating the heat and providing minute paths for the escape of the vapor or gases 50 arising or evolved upon the melting of the fusible element.

It is well appreciated that if a portion of 55 the fusible member is confined within an air space or if the air space is associated in a

suitable manner with respect to the fusible member that the melting point of the fuse may be figured to a greater degree of nicety. To this end I have cupped a portion of the 60 fusible member preferably to form an annular wall 15, which tapers or becomes narrower toward its outermost extremity. This narrowing of the metal is caused during the cupping action, it being understood that the 65 bottom of the cup is removed as an element of the fusible member. To confine the air within the space 16, formed by the cupping of the fusible member two disks 17 and 18 are provided for closing the ends of the annular wall 15. These disks either may be pasted to the fusible member 13 or may be held thereto by a bolt or nut arrangement 70 19, as shown in the figures of the drawing.

By having the metal forming the wall 15 75 tapered, and by having the closed air space 16 formed in the manner shown, the generated heat, caused by the passage of current through the fusible member is definitely known and this heat is retained within the 80 air space in a manner to cause the melting of the fusible member upon the occurrence of a predetermined load. This fusible member or fuse link may be described as having a pocket wherein generated heat is retained. 85

In this way a fuse is provided which will safeguard the circuit and the devices connected thereto in a manner to meet all the requirements for a successful operation.

It is my intention to cover all modifications falling within the scope of the following claims. 90

I claim:

1. In a fuse, a fusible member having a portion thereof cupped for providing an air 95 space within the fusible member, and means for closing the air space for confining generated heat.

2. In a fuse, a fusible member having a portion thereof cupped for providing an air 100 space within the fusible member, and disks for closing the ends of the cup in the fusible member for confining generated heat.

3. In a fuse, a fusible member having a portion thereof offset to form a recess therein, and means for inclosing the recess for 105 confining generated heat.

4. In a fuse, a fusible member a portion of which has its metal offset to form an air space, and means for closing the air space 110 for confining generated heat.

5. In a fuse, a fusible member a portion

of which is pressed forming a tapering wall, and means for confining generated heat adjacent the wall for increasing the sensitivity of the fusible member.

- 5 6. In a fuse, a fusible member having a portion thereof pressed laterally to form an inclosing wall, and means for closing the ends of said wall for confining generated heat.
- 10 7. In a fuse, a fusible member having the metal of a portion thereof pressed outwardly to form a continuous laterally extending

wall, and insulating members for closing the ends of said wall for confining generated heat therein.

8. A fuse link having a closed heat retaining pocket formed therein.

Signed at Chicago, Illinois, this 21st day of February, 1918.

ALFRED L. EUSTICE.
